SAFETY RAZOR

James Long, Dunedin, New Zealand

Application January 11, 1932, Serial No. 586,002

3 Claims. (Cl. 30—12)

This invention relates to safety razors, and apparatus used for shaving beards and for like purposes. In well known types there are several parts including a handle, a safety guard member, razor 5 blade and blade cap.

In well known types of safety razors, these parts on becoming detached from the handle are separate members: upon unscrewing the handle it disengages from the blade cap which is provided 10 with an external screw threaded stud, which projects sufficiently far enough to pass through the blade and through the guard member, and engages with an internally constructed thread in the handle. After washing the razor and upon assembly 15 there are four members to handle: generally the process is as follows: having the blade cap in hand the razor blade is placed thereon and then the blade guard so that the externally threaded stud projects through the blade guard, through 20 the hole made central therein and the handle is applied to the stud thus projecting to screw thereon and clamp the members together.

The construction thus described is objectionable in that it is required to wash the members separately, collect them separately, and assemble them 25 one member at a time.

The object of my invention is to overcome these objections.

According to my invention the razor cap and the 30 guard member are semi-detachable while the blade itself is wholly detachable and the handle is attached to the said guard member, having rotatable or/and slidably means associated therewith to engage with the cap for the purpose of 35 clamping the razor blade between the said cap and guard.

The invention will be more particularly described with reference to the accompanying drawing wherein:—

40 Figure 1 is a side elevation of the safety razor assembled.

Figure 2 is a sectional elevation of Figure 1, through the centre thereof.

45 Figure 3 is a cross sectional elevation showing a modification of the construction illustrated in Figures 1 and 2.

Figure 4 is a sectional elevation of further modification of the constructional features illustrated 50 in Figures 2 and 3.

Figure 5 is a part sectional elevation Figure 1, similar to Figure 2, the cap member being shown in disengagement with the handle member and turned on its pivot outwards,

55 Figure 6 is a still further modification of con-

structional features illustrated in Figures 2, 3 and 4.

Figure 7 is a part sectional elevation of the lower end of Figure 6 showing screw threaded means for turning the spindle, for stem engagement with 60 the blade cap, giving the same range of slidable movement illustrated in the said Figure 6.

Figure 8 is a plan view of the guard produced from Figure 5, all the parts below the said guard are omitted and the blade cap is diagrammatically indicated.

There is a blade cap 1, approximately the same shape as the existing one, with a screw threaded projecting stud 2 produced from the inner surface 3 thereof, and preferably two short metal 70 dowels 4, one of which is indicated in Figure 1, or their equivalents to engage the blade 5 and blade guard 6 for stability, and to assist in maintaining the blade in its normal shaving position after assembly.

There are suitable lugs 7 (preferably four) attached to the blade cap 1, which are disposed preferably one to each of the four corners of the said cap and produced therefrom, one pair on either side of the cap is adapted to register with lugs 8 on the blade guard 6 and be pivotally attached thereto. The other pair 7A are guide lugs and assist in retaining the blade 5 in position. As an alternative to the metal dowels there may be small ribs on the inner surface of the 85 cap to coincide with grooves in the blade guard, or alternatively a depression in the cap to engage with a rib or ridge on the blade guard to retain the blade in position.

The blade guard 6, which is also approximately the same shape as existing guards as to its general appearance, is provided with dowel holes 9 or alternative ridges or depressions for retaining the blade in position. If in manufacture 90 dowel holes 9 are accepted it is desirable that the said holes should be semi-countersunk as indicated at 9A to lead the metal dowels 4 into engagement when assembling the razor. In a like manner the hole 15 is semi-countersunk as indicated at 15A giving a lead to the screw threaded 95 stud 2.

There is a pivot pin 10 of small diameter attached to the lugs 7 formed on either end of the blade cap at the corners thereof, to form pivotal connection through the medium of lugs on the 100 blade guard 6. An alternative, describing an equivalent means to pivotally couple the blade cap and the blade guard, comprises links in pairs disposed on either end of the said cap and guard 105 at the corners thereof, the said links on the cap 110

and guard registering with each other in pairs, and pivotally connected so that the cap may turn thereon as in the manner of a hinge.

The handle 12 is preferably similar in appearance to the existing pattern, with the exception that it is secured to the blade guard through the medium of a sleeve 13, the hole 14 therein being disposed concentric with the hole 15 through the blade guard 6 on attachment. One end 10 of the tube forming the handle 12 is attached to the sleeve member 13, and at the other end of the said tube is fitted a cap member 16 which forms a bearing for a rotatable spindle 17, the end of which projects through the said cap bearing: a 15 head 18 is attached to the projecting part of the spindle and fixed thereto to render the said spindle rotatable by finger and thumb action on manipulating the head 18.

There is a slidable and rotatable member 19 20 part of which is housed within the tube forming part of the handle 12, and part of which is housed within the sleeve 13. There is an internal screw thread 20 cut in the part of the member 19 slid- 25 able within the sleeve 13 and in the part rotatable and slidable within the tube there is a slot 21 cut to engage with a pin 22 secured to the rotatable spindle, the ends of the said pin projecting beyond the diameter of the rotatable spindle 17 for the purpose of giving the slidable member 19 the desired range of its longitudinal movement within the sleeve 13 also for the purpose of rotating the said slidable member 19 by the finger and thumb action aforesaid, when applied to the rotatable spindle.

30 It is preferable that the portion of the slidable member 19 that is produced within a sleeve 13 is of smaller diameter than that portion of the slidable member 19 that is within the tube handle 12. This construction forms a shoulder 40 23 which is adapted to butt against the face of the sleeve member as in Figure 2, simultaneously with the conclusion of the maximum amount of strain applied to the head of the rotatable spindle for the purpose of clamping the razor 45 blade 5 between its cap 1 and guard member 6 and to prevent any undue strain.

As an alternative and in place of the slidable rotatable member, the spindle itself may be made slidable and rotatable as in Figure 6. In 50 this construction the cap bearing 16 is dispensed with permitting play between the end 12A of the tube member forming part of the handle and the bead 18A of the head 18 giving the desired range of longitudinal movement for the said spindle to recede to allow the blade cap member 1 with the blade 5 to engage the guard plate 6 before the externally threaded stud 2 on the blade cap 1 engages with the internally cut screw thread 20 on the top end of the slidable rotatable spindle 60 17, and upon turning the said spindle by the finger and thumb action applied to the head 18, the screw engages, and the play between the end 12A of the tube member and the said bead 18A of the head is taken up in the process of clamping the blade 5 between the cap 1 and guard 6 to fix 65 the said blade 5 in its normal shaving position. There is a collar 24 attached to the inner end of the spindle to limit the longitudinal movement and prevent the total withdrawal of the said spindle.

70 There is still another alternative in addition to the foregoing described construction, comprising a screw thread 25 cut internally in the handle tube and a screw thread 26 cut externally on the spindle, the length of thread cut both externally

and internally being a little more than the amount of play allowed between the end of the tube and the bead 18A in the head member 18. This method renders the spindle 17 fixedly rigid and the play in the spindle 17 is taken up solely 80 in the process of rotating the spindle 17 and is not slidable otherwise.

In the modification illustrated in Figure 3, the handle 12 rotates while the sleeve 13 is stationary and fixed to the guard 6. The slidable motion in the rotatable slidable member described in the other modifications is done away with and in place of being slidable the rotatable member 19A is fixed to the handle member 12 so that it rotates with the said handle without any slidable movement. The said rotatable member 19A is produced beyond the upper end of the handle member, providing means for rotatable conjunction with a sleeve member 13, a part of the rotatable member 19A projecting beyond the handle is 95 bored and screw threaded at 20A to register with the screw threaded stud 2 (omitted in this figure) on the blade cap. There is a collar 20B formed at the top end of the produced part to prevent disengagement of the handle member and the sleeve 100 13. In this construction there is provision for the blade cap 1 (not shown in this figure) to have sufficient play so that the stud 2 thereon when assembled permits the first thread of the screw to engage without any danger of crossing the said 105 thread, comprising a slot as indicated at 11A in the lug 11 for a pivot 10 instead of a round hole to receive the pivot pin as indicated at 10 in the other figures.

Referring again to Figure 8, instead of the 110 edges of the guard 6 having projections 27 in the usual way, it may be desirable for the inclusion of a reinforcing bar from end to end of the guard integral with the said teeth forming slots which would be preferably elongated to give greater 115 clearance to free the lather and beard, in the process of shaving. The construction as suggested herein is indicated by dotted lines at 28, Figure 8.

In the new manufacture and assembly of the 120 several parts, it will be readily understood from the foregoing description of my invention that the razor blade 5 is the only separate member, and its application to the cap 1 is a simple process. Upon disengaging the internally screw threaded 125 slidable member 19, and the externally screw threaded stud 2, the cap 1 may swing on its pivot 10 through an arc, approximately ninety degrees as indicated in Figure 5, and the blade being applied to the face of the cap, engaging the 130 metal dowels and the stud, is held loosely thereon, and is, in addition to the said dowel or screw, in a measure prevented from slipping or falling off the cap by the lugs 7 and 7A attached to the said cap, and renders it practicable for the outfit to be washed without dismembering any part of it.

To replace the cap 1 and blade 5 to normal 140 shaving position, either the cap member 1 or the guard 6 may be turned on the pivot 10, the metal dowels 4 in the cap 1 engage with the holes 9 in the blade guard 6, the stud 2 in the cap 1 engages with the threaded slidable member 19 in the handle 12 and upon turning the head 18 on the said handle 12 to rotate the said slidable 145 member 19, the screw thread engages and the blades is clamped between the guard and the cap.

What I claim as new and desire to secure by Letters Patent is:—

1. In combination with a guard member, a cap member having loose pivotal connection therewith a spindle, a non-rotatable and non-slidable tubular handle having a sleeve-like extension at one end thereof, a rotatable and slidable member slidable on the said spindle and rotatable therewith, and having part thereof rotatably and slidably disposed within the said non-rotatable and non-slidable tubular handle and part within said sleeve-like extension of the said handle, and means on said cap member engageable with said rotatable and slidable member to secure the cap member in position. 80
2. In combination with a guard member, a cap member having loose pivotal connection therewith, a rotatable spindle, a rotatable and slidable member 90
- having an internal screw thread cut in the top end thereof for screw engagement with an external screw thread cut on a stud projecting from said cap member, the said slidable and rotatable member having a slot formed in the lower end thereof, a driving pin projecting beyond the diameter of the said rotatable spindle and engaging said slot. 85
3. An arrangement as claimed in claim 2, characterized by the provision of a non-rotatable and non-slidable tubular handle receiving said spindle and having a sleeve-like extension, said rotatable and slidable member being received partly in said handle and partly in said extension. 90
